UNITED STATES PATENT OFFICE

2,333,073

CHAIR

Frederick H. Mueller, Grand Rapids, Mich., assignor of one-half to Mary D. Mueller, Grand Rapids, Mich.

Application May 5, 1942, Serial No. 441,857

5 Claims. (Cl. 155—196)

This invention relates to an economically produced chair of rugged construction which may be fabricated without complicated machinery or essential materials. The chair is of particular use in reasonably priced housing where it is desirable to have a comfortable, rugged chair which is readily set up or demounted. Essentially, the present construction is such that this improved chair may be made in four major pieces, namely: two side units which engage the ground and form the vertical sides and arms and between which the seat portion and back are supported by integral dovetail slots formed in the inner surfaces of the side units.

In the drawing:

Fig. 1 illustrates a side elevation of the complete chair, showing the relationship of the several units or parts.

Fig. 2 is a front elevation showing the manner of positioning the seat and back portions with respect to the side units.

Fig. 3 is a vertical section taken on line 2—2 of Fig. 2, looking in the direction of the arrows to disclose the relationship of the seat and back to one side unit.

Fig. 4 is a plan view of the inner side of one of the side units.

Figs. 5, 6 and 7 are enlarged details of construction.

One of the salient features of this invention is the construction and fabrication of the side units as illustrated in Fig. 4. Here an elongated longitudinal runner or ground engaging member 1 is formed with a rounded front portion 3 and a rearwardly extension 5 with a pedestal base 7 thereon to which is attached an upstanding rearwardly inclined bar or side frame member 9. At the front end of the runner 1 there is mounted a comparatively wide vertical riser 11, and as shown, the front and rear members 9 and 11 are joined at their upper ends by a one-piece combined side brace and arm 13 having their ends rounded to give a pleasing appearance and a symmetrical configuration.

The inner faces of each vertical member 9 and 11 of each side unit are provided with horizontally aligned dovetail grooves or slots 15 and 17 for the reception of a cooperating dovetail 19 formed on the opposite parallel sides of a rectangular frame 21 carrying a flat upper panel 23. This frame and panel with its side dovetails, when inserted in the dovetail slots 15 and 17 of the side units, forms the seat or weight-supporting portion of the chair. The position of the

seat frame is maintained by having the front edge of the frame 21 finished with a front bar 25 which extends outwardly beyond the bottom of the dovetail slide slots 15 in the vertical risers 11.

The inner faces of the upwardly extending oblique side bars 9 are similarly provided with dovetail grooves 27 for the reception of dovetails 29 formed in the sides of a rectangular frame 31 which carries a panel 33 and forms the rear portion or back of the chair. As shown in the drawing, the dovetail grooves 17 and 27 intersect and consequently the back frame 31 extends downwardly and rests on and contacts the rear bar of the seat frame 21.

It would be observed that the rearward upstanding oblique arms of the side units are secured to the flat longitudinal ground engaging members inwardly from the rear ends thereof and that the rear ends of the horizontal arm portions terminate slightly within the length of the ground engaging members. This creates inherent stability in the chair and prevents its tipping over backward when in use.

If desired, suitable pads or upholstery may be attached to both the bottom and back frames or a single upholstery pad having upper and lower cushions joined by a web may be fitted across the back and seat of the chair.

This improved chair construction may be used for both wood and plastic structures or a combination thereof. The side units are easily fabricated from comparatively small pieces of lumber and are joined by suitable dowels, screws, pins or the like, or they may be molded as an integral unit. The seat and back panels may be composed of plywood, fiber or similar materials.

One of the advantages of the present construction, aside from its economical construction, is the fact that no essential materials are used in its manufacture and the entire piece of furniture is easily constructed with unskilled labor and simple machinery. A further advantage is that the chair may be shipped in knock-down condition and put together without the least difficulty.

What I claim is:

1. A chair comprising a pair of spaced apart side units, each unit comprising a flat longitudinal ground engaging member and having a front upstanding riser and rear upstanding oblique bar secured thereto, the upper ends of said riser and bar being joined by a horizontal arm por-

tion, horizontal aligned dovetail slots in the inner sides of said risers and rear oblique bars, a seat portion comprising a rectangular panel having complementary side projections for engaging said horizontal aligned slots, and vertical dovetail slots formed in the inner sides of said rear oblique bars, for engaging complementary projections formed on sides of a second rectangular panel forming the back of said chair.

2. A chair as defined in claim 1, wherein the 10 horizontal and vertical slots in each rear upstanding oblique bar intersect each other.

3. A chair as defined in claim 1, wherein the side units, and seat and back panels are secured

together solely through the medium of the horizontal and vertical dovetail slots cooperating with the said complementary side projections.

4. A chair as defined in claim 1, wherein the side units are formed as an integral one piece molded plastic structure.

5. A chair as defined in claim 1, wherein the rearward upstanding oblique bars of the side units are secured to the flat longitudinal ground engaging members inwardly from the rear ends thereof and the rear ends of the horizontal arm portions terminate slightly within the length of said ground engaging members.

FREDERICK H. MUELLER.
